UNITED STATES PATENT OFFICE

ARTHUR TREVOR DAWSON AND GEORGE THOMAS BUCKHAM, OF WESTMINSTER,
LONDON, ENGLAND, ASSIGNORS TO VICKERS LIMITED, OF WESTMINSTER,
ENGLAND.

BALL-AND-SOCKET JOINT.

1,304,270.

Specification of Letters Patent.

Patented May 20, 1919.

Application filed June 16, 1915. Serial No. 34,545.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Ball-and-Socket Joints, of which the following is

10 a specification.

This invention relates to ball and socket joints; it is usual to employ a screw threaded plug engaging with the socket for the purpose of retaining the ball in the socket 15 and of enabling the said ball to be placed in position and removed when desired. The chief object of the present invention is to avoid the necessity of employing the screw-threaded plug, thereby reducing the weight 20 of the parts and obviating any weakening of the socket member, as a result of the cutting away of the material for the reception of the said plug.

According to this invention we divide the 25 ball member into two parts (preferably halves) in a plane at right angles to the ends of the member that carries or passes through the ball member (which member may be in the form of a spindle or the like) 30 the inner surface of the socket being formed with slots or gaps of appropriate size and shape to enable each of the two parts of the ball member to be passed through edgewise and to be moved together into the operative 35 position for the reception of the aforesaid spindle or the like. The two parts may be locked together in any suitable manner, for example by means of a dovetailed key and keyway, one formed on each part, so that as 40 the second part is being passed through the slots or gaps in the socket the key and keyway engage with one another. The two parts may be further secured against relative sliding movement along the key, by a 45 screw engaging with each part.

In order that the said invention may be clearly understood and readily carried into effect we will describe the same more fully with reference to the accompanying drawings, in which:—

Figure 1 is a sectional elevation showing a constructional form of the invention applied by way of example to the cross-bar for connecting the trail beams or members of a divided-trail gun carriage, this cross-bar hav-

ing a ball member rigidly connected thereto at each end and at its center carrying another ball member in which the training pivot is rotatably mounted.

Fig. 2 is a view similar to the right hand portion of Fig. 1 showing the socket with the ball member removed.

Fig. 3 is a plan of Fig. 1 viewed from beneath.

Fig. 4 is a side elevation of the center ball member and its socket viewed in the direction of the arrow in Fig. 1.

Fig. 5 is a plan of the ball member shown in Fig. 4 and

Fig. 6 is a view of the right hand socket 70 of Fig. 3 viewed in the direction of the arrow in Fig. 3.

A, A are the trail beams or members, B is the connecting cross-bar. C is the training pivot moving with the carriage or with a 75 frame supporting an upper carriage. D, D represents the ball members one connected to each end of the cross-bar B and disposed in sockets D', D' in the trail beams, and E represents the central ball member carried 80 by a socket E' in the cross-bar and serving to rotatably receive the training pivot C.

As shown in the drawings the ball members D, D and E are made in two parts each of which is in the form of a ring having a 85 spherical periphery; when in position within the socket they are connected together by means of a dovetailed key and keyway arrangement (see Figs. 3 and 4) and also, if desired, by screws d, d, e engaging with each 90 part for preventing relative sliding movement along the keys.

D², D², E², represent the slots or gaps in the sockets D', D', E' through which one part of each of the ball members D, D, E is 95 first inserted edgewise and is then turned through an angle of 180 degrees about the axis of the cross-bar B or of the training pivot C. The other part of the ball member is then inserted edgewise through the 100 said slots or gaps and this movement causes the two parts of the ball members to be united by the dovetailed key and keyway above referred to; the ball member as a whole can then be angularly displaced into 105 the required position and the screws d, d, e then inserted.

After the ball members D, D have been caused to occupy the correct positions in their sockets, they are held by means of 110

tommy bars passing through holes d' , d'' in the sockets and corresponding holes d^2 , d^2 in the ball members to enable the cross-bar to be screwed into the said ball members.

5 The aforesaid securing screws d , d are also adapted to engage with screw threaded holes in the cross-bar for the purpose of preventing the latter from rotating about its axis relatively to the ball member. With the ball

10 member E the above mentioned expedients are of course unnecessary as the training pivot is rotatable within the ball member.

The aforesaid slots or gaps D^2 , D^2 , E^2 , in the sockets for permitting the parts of the ball member to enter may be parallel to but at one side of the axis of the bar and the pivot, or they may be as shown at an angle to the said axis in which case the center of the slots or gaps may coincide with the said axes. The said cross-bar may be arranged directly beneath or to the rear of the axle tree.

What we claim and desire to secure by Letters Patent of the United States is:—

25 1. In a ball and socket joint, a ball member comprising two parts, each in the form of a ring having a spherical periphery and a socket member formed with apertures through which each of the parts of the ball

30 member can be passed edgewise.

2. In a ball and socket joint, a ball member comprising two parts, each in the form of a ring having a spherical periphery, a socket member formed with apertures

through which each of the parts of the ball member can be passed edgewise, said parts having means whereby as the second ball member part is being placed in position in the socket it will become united with the first ball member part.

3. In a ball and socket joint, a ball member comprising two parts each in the form of a ring having a spherical periphery, a socket member formed on its face with apertures through which each of the parts of the ball member can be passed edgewise, said parts having means whereby as the second ball member part is being placed in position in the socket it will become united with the first ball member part.

4. In a ball and socket joint, a ball member comprising two parts each in the form of a ring having a spherical periphery, a socket member formed on its face with apertures through which each of the parts of the ball member can be passed edgewise, one ball member part having a key and the other part having a keyway adapted to engage therewith so that as the second part is being placed in position in the socket it will become united with the first part.

In testimony whereof we hereunto affix our signatures.

ARTHUR TREVOR DAWSON.
GEORGE THOMAS BUCKHAM.
